UNITED STATES PATENT OFFICE.

GUSTAVE M. KAEMPFFE, OF PEETZBURG, NEW JERSEY.

WINDOW FRAME AND SCREEN.

1,370,214.

Specification of Letters Patent.

Patented Mar. 1, 1921.

Application filed November 5, 1919. Serial No. 335,841.

To all whom it may concern:

Be it known that I, GUSTAVE M. KAEMPFFE, a citizen of the United States, residing at Peetzburg, in the county of Bergen and State 5 of New Jersey, have invented certain new and useful Improvements in Window Frames and Screens; and I do hereby declare the following to be a full, clear, and exact description of the invention, such as 10 will enable others skilled in the art to which it appertains to make and use the same.

This invention relates to screens, and more particularly to full length screens for windows.

15 The objects of the invention are to provide a full length screen which may be easily gotten out of the way for such purposes as washing the outside of the window; to provide such a screen which will not be liable to 20 dislodgment during the opening process; to permit a portion of the screen to be opened where desired; to provide a screen which can be reduced to a compact dimension for carrying through a house or storing 25 and so forth; to obtain rigidity, strength, durability, neatness and simplicity of construction; to provide a structure which is susceptible to sale in a knock-down condition and readily assembled, and to obtain 30 other advantages and results as may be brought out in the following description.

Referring to the accompanying drawings in which like numerals of reference indicate the same parts throughout the several views,

35 Figure 1 is a perspective view of a screen embodying my invention, shown mounted in position in a window opening;

Fig. 2 is a perspective view of the screen in partly collapsed condition;

40 Fig. 3 is a detail perspective view of the joint between the screen frame sections;

Fig. 4 is a perspective view similar to Fig. 1 and showing a slightly modified form, and

45 Fig. 5 is a vertical sectional view of the frame and foraminous members carried thereby.

It has been common practice heretofore to provide full length screens for window openings, the screens often being hinged at 50 their top to swing upwardly outward, and usually the hinge is so constructed that the screen may be lifted off of it when said screen is swung out. It has been found in practice that such a screen is very often 55 pushed upon above its center of gravity, and

after it swings out a little ways, the components of force acting upon it will lift it from its hinge, whereupon it drops to the ground. Furthermore, such a screen has to be propped high in the air when someone 60 washes the window for instance, and during such operation, the prop is very often dislodged, causing damage to the screen. Furthermore, such a screen does not permit laying of articles across the window sill and 65 closing the screen down tight upon the articles without leaving a crack at the side of the window. The present invention contemplates overcoming these difficulties and disadvantages in addition to the advantages 70 and objects already outlined.

In the specific embodiment of the invention illustrated in said drawing, the reference numeral 1 indicates a window frame to which my invention is applied. A screen 75 frame 2, of a size to fit within said window frame, is mounted by means of shutter hinges 3 to said window frame 1, said hinges being adjacent the top and bottom of the frame at one side so that said screen frame 80 is swung upon a vertical axis much the same as a door is swung. Preferably said screen frame is made up of an upper section 4 and a lower section 5 which are hinged together as by hinges 6, 6 to fold upon a 85 horizontal axis. By this means, the screen frame is adapted to double near its middle so that the top part may fold down against the lower part of the frame. This folding of the frame is for convenience in handling 90 the screen and for storing it, the length being thus reduced, permitting the screen to be more easily carried through a house and around sharp corners on stairs, and so forth. Furthermore, the screen being thus short- 95 ened, may be tucked away in a corner or elsewhere and not protrude out in the way, thus adding to the desirability of the screen.

In order to retain the frame rigid while mounted upon the hinges 3, cleats 7, 7 are 100 provided which overlap the meeting ends of the upper and lower sections 4 and 5, screws 8 securing the cleats to both of the sections. The cleats are preferably directly opposite the hinges 6 by which the sections are hinged 105 together and coöperate therewith to form a rigid structure, but by removal of the screws from one section, the hinges will be allowed to function, thus permitting the sections to be folded together when desired. Obvi- 110

ously, other means than the cleats 7 may be employed, and I do not wish to be understood as restricting myself specifically thereto.

- 5 In order to permit the screen to be opened in part, as for instance, when it is desired to lay some article across the window sill, a slidable member A is provided within the screen frame, said slidable member being
10 substantially one-half the height of the frame and adapted to be slid from one section into the other. The slidable member is formed in any suitable manner as for instance, of a foraminous material 9 sur-
15 rounded by a rim 10, the side strips of which have slidable engagement with the screen frame 2 as by groove B in said frame. As may be seen in Fig. 2, this slidable member is of a size such that it may be slid entirely
20 within one section of the screen frame and preferably the section into which it is slid is the upper section 4, said upper section being enough longer than the lower section to permit the said slidable member to remain
25 with its upper edge within the upper section when closed down to the sill of the screen frame 2. This permits the slidable member to overlap and form a closure with a screen member within the upper section.
30 While it is within the scope of the present invention to mount the upper screen member slidably, in the present embodiment, said upper screen member is made fast with respect to the upper section 4, and for illus-
35 trative purposes, is shown as comprising a foraminous member 11 carried by a sur-
rounding rim 12. By making this upper member rigid with respect to the section 4, said section is braced and thereby kept from
40 sagging at its outer corner. The same effect may be obtained, however, by attaching the foraminous member 11 directly to the strips making up the section 4, thus omitting the intervening strips 12. This structure may
45 be, for instance, as shown in Figs. 4 and 5 wherein reference numeral 13 indicates the window frame to which is hinged a screen frame 14 as by hinges 15 similar to the structure previously described. Said screen
50 frame is furthermore composed of upper and lower sections 16 and 17 respectively hinged together, as at 18, and adapted to be maintained in extended position by cleats 19 as will be understood from the description
55 of the embodiment previously set forth. The lower section 17 likewise normally carries a slidable foraminous member 20 which is preferably slidable as in grooves 20' of the frame, thus permitting said member to
60 be raised when desired for obvious purposes. The upper section, however, has a forami-
nous member 21 which is fixed with respect to the section so as to strengthen and brace said section. Said member 21 is preferably
65 attached directly to the frame section. As

usual, beading 22 may be employed to cover the edge of said member.

Obviously, other detail modifications and changes may be made in the construction and assemblage of my improved screen, and I do not wish to be understood as restricting myself except as set forth in the following claims when construed in the light of the prior art.

In use and referring by numerals to Figs. 1 to 3 more particularly, the screen is assembled as an extended unit of a size to fit the window opening, the hinges 6 between the upper and lower sections functioning as means for holding the sections together and cooperating with cleats 7 for retaining the sections 4, 5 in rigid extended position. When it is desired to get access to the outside of the window as for cleaning, the screen frame 2 comprising sections 4 and 5, is swung outwardly upon the hinges 3, thus exposing the entire window without any likelihood of the screen being pushed from its hinges or otherwise becoming dislodged. While the screen is closed, it will be obvious that the lower member may be raised as can an ordinary half screen commonly found upon houses, and in so raising this lower section, the remainder of the screen including frame 2, remains in its place. When it is desired to store the screen, it may be lifted from its hinges and by removal of the screws 8 from the cleats, may be then doubled at its middle by virtue of hinges 6 and easily carried through the house and stored away.

Having thus described my invention, I claim:

1. A full length screen for closing the entire window opening, comprising a frame of a size substantially that of the window opening having hinges near its top and bottom whereby said frame may be supported in the window opening and swung into and out of position, said frame having a second pair of hinges arranged on the opposite side members of the frame and adapted to permit said frame to be doubled at substantially its middle, a foraminous closure for the portion of said frame above said second mentioned hinges for bracing the frame and preventing the same from sagging and at the same time permitting entry of light and air, said frame having grooves in a common plane on the normal arrangement of the screen, and a slidable frame mounted in said grooves adapted to be slid up and down therein.

2. A full length screen for closing the entire window opening, comprising a frame of a size substantially that of the window opening having hinges near its top and bottom whereby said frame may be supported in the window opening and swung into and out of position, said frame having a second pair of hinges arranged on the opposite side mem-

bers of the frame and adapted to permit said frame to be doubled at substantially its middle, a foraminous closure for the portion of said frame above said second mentioned 5 hinges for bracing the frame and preventing the same from sagging and at the same time permitting entry of light and air, said frame having grooves in a common plane in the normal arrangement of the screen, and a

slidable frame mounted in said grooves 10 adapted to be slid up and down therein, the upper section of said frame having greater depth than the lower section, and said slide-able frame being of the same depth as the upper frame so as to always be partially 15 or wholly within the upper section.

In testimony whereof I affix my signature.
GUSTAVE M. KAEMPFFE.
